SOLE-SEWING MACHINE.

1,171,714.

Specification of Letters Patent. Patented Feb. 15, 1916.

Application filed June 30, 1913. Serial No. 776,583.

To all whom it may concern:

Be it known that I, JOHN WILLIAM GODDARD, a subject of the King of Great Britain, residing at Leicester, in the county of Leicestershire, England, have invented certain new and useful Improvements in Sole-Sewing Machines; and I do hereby declare the following to be a full, clear, and exact description of the invention, such as will enable others skilled 10 in the art to which it appertains to make and use the same.

This invention relates to lock stitch or other sole sewing machines of that type in which the work support is in the form of a 15 horn.

The object of this invention is to improve machines of this type so that the quality of the stitches is improved and the rapidity with which they are formed in the work is 20 increased over machines as heretofore constructed.

It is desirable in lock stitch sewing machines that the looping of the needle thread around the bobbin case that contains the 25 locking thread shall occupy as short a time as possible in each cycle of operations so as to afford sufficient time for the operation of other parts of the machine; and it is also desirable that the means for looping the 30 needle thread over the bobbin case shall have a continuous rotary motion to obviate the loss of energy due to inertia in stopping and starting moving parts of the machine.

With these ends in view the invention 35 comprises for a lock stitch sole sewing machine having a work-supporting horn and a reciprocating needle bar carrying a barbed needle that penetrates and then draws through the work a loop of thread from a 40 looper in the supporting horn, the combination of a discoidal shuttle arranged to rotate about an axis that is so inclined with relation to the path of the needle that the body portion of the shuttle is clear of the 45 needle bar when the beak of the shuttle is taking the loop of thread from the needle, and devices for reciprocating the shuttle bodily in an approximately axial direction, first to cause the beak to engage the loop of 50 thread drawn by the needle, and then to cause the beak to clear the needle and needle bar during succeeding rotations of the shuttle.

By arranging the shuttle so that it ro-

tates about an axis inclined to the path of the needle, a short and consequently a rigid needle is capable of being used in the machine, and by providing devices for reciprocating the shuttle bodily in an approximately axial direction the shuttle can be 55 supported and actuated without interfering with the manipulation of the shoe, and the shuttle while being rotated at high speed can be presented to the thread at the proper time in the cycle of operations and can be 60 then withdrawn to allow other parts of the machine to do their work.

In lock stitch sewing machines it is found that the loop of thread drawn up by the needle is sometimes moved so far aside by 70 the turning of the work that it is caused to miss the beak of the shuttle and to overcome this difficulty a further feature of this invention consists in a device operating in the space between the shuttle and the work 75 for deflecting the loop of thread to a definite position in relation to the shuttle beak just previously to the beak entering the loop. This device is preferably operatively connected with the needle bar and conveniently it comprises a lever of which one end is arranged to engage the loop of thread between the shuttle beak and the work and the other end to be acted upon by a cam on the needle bar. 80

In machines of the type above referred to there is usually a whirl located in the tip of the horn, the function of which is to wrap the thread around the needle after the needle has pierced the work. The thread is guided 90 from the eye or thread passage in the whirl along the horn to a thread-restraining device, for example a locking device which locks and unlocks the thread at suitable times in the operation of the machine. The 95 thread whirl and the mechanism which drives it is so arranged in relation to the horn that the turning of the horn by the operator during the sewing of the boot around the edge of the sole does not alter 100 the angular position of the whirl in relation to the needle. It is found, however, that with the eye in the thread whirl located as usual to one side of the axis about which the horn is turned by the operator that as 105 the horn is rotated the length of the bight of thread extending between the locking device and the whirl is varied and consequently

the stitches formed are not of uniform character.

The provision of devices to remove or mitigate this disadvantage is a feature of the present invention. For example, the whirl, which is necessarily of small size, both in diameter and thickness, can be provided with a thread eye or passage, the underside thread receiving orifice of which is approximately central with the axis of the whirl, while the delivery end is to one side of the axis of the whirl in position to lay the thread around the needle barb. The needle barb at such times can be arranged to lie in a hole in the whirl that at its upper end is central with the axis of the whirl, but then deflects to one side so that it finds its lower outlet at one side of the central thread-receiving orifice in the underside of the whirl. The degree to which the needle-receiving hole would be made to deflect would correspond with the shape of the side of the taper point of the needle, and the hole itself would be of full size throughout its length so that the wax and thread fluff which normally accumulates in such whirls might pass through the said hole and leave sufficient clearance room for the barb of the needle.

If the thread-receiving orifice of the eye in the whirl is not made exactly central there may be provided means that, as the horn is rotated, automatically maintain constant or substantially constant the length of the bight of thread between the whirl and the locking device. This automatic means may comprise a thread guide between which and the horn there is relative movement during the turning of the horn, the said movement being to such an extent that the length of the bight of thread will be maintained constant or substantially constant in every position of the horn. One construction of the said automatic means that comes within the present invention comprises a thread guide which is located, with relation to the thread eye in the whirl, upon the opposite side of the axis about which the horn rotates and which is so operatively connected with the whirl that its position in relation to the same during the turning of the horn is maintained constant, and a thread eye carried by or movable with the horn and engaging the bight of thread at a point between the whirl and the said thread guide.

A further object of the invention is to provide an improved whirl, the driving parts of which are completely protected from wax deposit and thread fluff and which are stronger than those of whirls as heretofore constructed. A feature of the invention therefore is a whirl in which the thread eye orifice on the thread-receiving face of the whirl is nearer to the axis of the whirl than the orifice on the thread-delivering face and

in which the driving teeth of the whirl are located adjacent the thread-receiving face thereof, or are located in such a position that they may be engaged by a driving pinion that does not extend to or project beyond the thread-delivering face of the whirl. In such a construction of whirl the bevel wheel which is employed to drive the whirl can be of a larger diameter than heretofore inasmuch as the driving teeth on the whirl with which it engages may be located either on the end of or on a portion of the whirl remote from the top of the horn and consequently there is more room for the driving mechanism of the whirl. Furthermore the driving parts can be more completely enclosed than in the prior constructions.

These and other features of the invention including certain details of construction and combinations of parts will now be described in connection with a preferred construction according to the present invention, but it is to be understood that the invention is not to be considered as limited to such a construction as it could be embodied in other ways without departing from the spirit thereof.

In the drawings: Figure 1 is a front elevation of the machine with the base of the machine, the lower part of the horn and the needle and presser foot actuating devices shown broken away; Fig. 2 is a side elevation of the same partly in section; Fig. 3 is a plan of the shuttle, shuttle carrier and their operating mechanism; Fig. 4 is a vertical section through the center of the base of the horn; Fig. 5 is a detail plan of the whirl; and Fig. 6 is a vertical section through the tip of the horn showing the whirl and its driving pinion and the needle in operative position relative thereto.

Like reference characters indicate like parts in all the drawings.

The machine comprises a work-supporting horn 1, a straight hook needle 2 mounted above the horn and arranged to reciprocate in a vertical direction to enter the horn after passing through the work, a presser foot 3 and a rotary shuttle 4 which engages the loop of thread pulled through the work by the needle and passes it around a stationary bobbin case containing the locking thread.

The shuttle 4 is mounted in the machine so as to rotate in a plane inclined to the axis of the needle and makes two complete rotations during each cycle of operations of the machine. During one of these rotations the loop-taking beak 5 of the shuttle passes near or through the path of movement of the needle and engages the loop of needle thread held in the needle barb while during the second rotation the shuttle is retracted so that while the needle is entering the work the shuttle is free to rotate without fouling the needle or the needle-carrying mechanism.

Referring to Figs. 2 and 3, the shuttle comprises a cup-shaped body arranged eccentrically in a supporting flange 6 the flange being mounted for rotation in a plane 5 inclined to the vertical within a shuttle-carrying casing 7 and a cover plate 8. The casing has a sleeve 9 extending rearwardly through a bearing in the frame of the machine in which the sleeve is longitudinally 10 movable. In order that the shuttle may be moved into and out of the line of movement of the needle the shuttle-carrying casing, together with the shuttle driver which it contains, is reciprocated in the frame of the 15 machine in a horizontal direction. The shuttle driver 10 consists of a lever having two projections 11 extending forwardly from the opposite ends of the lever and arranged to enter recesses in the back of the 20 body of the shuttle. This shuttle driver is pivoted at 12 to the end of a short shaft 13 carried in a bearing in the sleeve 9 and its rearward surface engages a cam 14 surrounding the said short shaft but fixed relatively to the casing 7. The shaft 13 is 25 rotated within the sleeve 9 and the cam 14 is so shaped that the shuttle driver 10 is tilted on its pivot 12 sufficiently to cause both projections 11 to engage the shuttle except at such points of the revolution as it is required that the thread, in being looped over the shuttle, shall pass a projection, at which time that projection is moved out of engagement with the shuttle. This action is 30 aided by the inclination of the axis of rotation of the shuttle to that of the shuttle-driving shaft but if desired it may be caused by the said inclination alone in which case the part 10 that carries the projections 11 35 instead of being pivoted upon the shaft 13 will be rigidly secured to it and the cam 14 will be omitted.

The shaft 13 carrying the shuttle driver is held from endwise movement in the sleeve 45 9 by a thrust block 15 which is screwed over the rear end of the shaft so as to abut against the rear end of the sleeve. To prevent the casing 7 from rotating with the shaft 13 any convenient means may be provided.

In order to rotate the shuttle driver a horizontal driving shaft 16 enters the rear end of the shaft 13 which is bored out to receive it, the two shafts being maintained in 50 driving connection by keys 17 which are connected to the driving shaft and enter grooves in the bore of the shaft 13. Upon the rear end of the horizontal driving shaft is mounted a spiral 55 gear wheel 18 which meshes with a second spiral gear wheel 19 carried by an approximately vertical shaft 20. This vertical shaft is rotated once during each cycle of operations of the machine and the sizes of the gear 60 wheels are such that the horizontal shaft 16

is driven at twice the speed of the vertical shaft so that it makes two rotations during each cycle of operations.

In order that the shuttle may be reciprocated toward and from the path of movement of the needle as above mentioned, the sleeve is connected by a link 21 to an eccentric 22 mounted upon the vertical shaft 20 below the spiral gear wheel 19. Accordingly the link connecting the eccentric and the 70 sleeve will have a slight vertical movement as well as a lateral reciprocating movement. The link therefore is connected to the sleeve by a universal joint comprising two lugs 23 projecting from the sleeve, a pin 24 passing through the lugs and a forked pivotal connection between the pin and the link. The arms of the fork where they lie between the two lugs are rounded and are of such a 75 diameter as to engage with both of the said lugs in order to prevent any slackness in the joint. The other end of the link is connected to the eccentric by an eccentric strap 25 and to permit of the different motions of the link the engaging surfaces of the strap and eccentric are spherical. 80

The stationary bobbin case 26 (Fig. 1) containing the locking thread is mounted loosely within the cup-shaped body of the shuttle and is retained in place by the forward end of a horizontal arm 27 arranged to lie in front of the bobbin. This arm is pivoted at 28 to swing horizontally upon an extension from the shuttle casing. The other end of the arm projects beyond its pivot and has a notch cut in it which is engaged by a tooth upon the lower end of a pin 29 mounted in a bearing 30 in the projection from the shuttle casing (see Figs. 1 and 3). The upper end of this pin has a handle 31 by means of which the operator may rotate the pin and so turn the horizontal arm about its pivot in a direction to move its forward end away from the shuttle so as to enable the bobbin case to be removed 95 from or placed within the shuttle, the construction being the same as that illustrated and described in the patent to W. C. Meyer, dated December 31, 1912, No. 1,048,565. Upon the operator releasing the handle a 100 spiral spring 32 connected with the vertical pin rotates it in the opposite direction and brings the forward end of the horizontal arm into position to hold the stationary bobbin case in place. An adjusting screw 33 is 105 provided in the horizontal arm which engages the shuttle casing and limits its movement due to the spring. 110

In order to prevent the stationary bobbin case from rotating and at the same time permit the loop of needle thread to pass over it there is formed on the face of the bobbin case a projection 34 (see Figs. 1 and 2) which loosely enters a slot cut in the forward end of the horizontal arm 27. This 115 120 125 130

projection is so shaped that the loop of needle thread passes easily between it and the sides of the slot.

Pivoted at 35 to the frame of the machine 5 is a lever 36 extending downwardly to just above the work and having its lower end bent back toward the axis of the needle. This lever is operated when the needle is at the upper limit of the stroke by a tappet 10 cam 37 on the needle bar, acting on the lever about its pivot to force the lower end back causing it to engage the loop of thread drawn up by the needle and to deflect said loop in front of the shuttle beak irrespective of the position at which it leaves the material. A spring 38 (see Fig. 1) retracts the lever out of the way of the needle when the pressure of the tappet cam 37 is removed by the descent of the needle bar and an adjustable stop 39 prevents the lever from moving inwardly too far under the influence of its momentum.

The work-supporting horn 1 of the machine is mounted so as to turn about a vertical axis in line with the axis of the needle. The top of the horn is pierced by a hole 40 (see Fig. 6) through which the needle passes and mounted within the horn just below this hole is a looper in the form of a whirl 41 25 having for the needle thread an eye or passage 42 the delivery end of which is positioned eccentrically but which approaches the center of the whirl at its thread-receiving end. In the whirl is an opening 43 to receive the needle, almost central at its upper end, but bending away to avoid the thread eye 42 at its lower end and passing right through the whirl to allow of the escape of wax and thread fluff which tends to 30 collect in it. In order that the needle thread may be looped about the needle during each cycle of operations of the machine the whirl is rotated by means of bevel gear teeth 44 formed upon the whirl and engaging 35 with bevel teeth 45 cut on the end of a shaft 46 which is carried in bearings within the horn. The bevel teeth are cut around the base of the whirl as shown in preference to being cut as heretofore around the upper 40 edge, since it is found in this way possible to use a larger driving bevel wheel and the gearing is completely protected from the entrance of dust and thread fluff, which has not been the case in previous constructions. 45 This modification of the position of the bevel teeth on the whirl is rendered possible by the use of a thread eye approaching the center of the whirl toward its base, which thus allows room for the teeth without making the whirl of undue size.

The shaft 46 is rotated through suitable connections by a second shaft 47 (see Fig. 4) mounted to rotate in the base of the horn and having secured to its lower end a bevel 55 gear wheel 48. This gear wheel is in engage-

ment with a power-operated bevel gear wheel 49 secured upon a hollow vertical driving shaft 50 which also forms the pivot about which the horn is turned.

It will be understood that the center line 70 of the needle projected downward lies along the axis about which turn both the horn and the whirl in the horn. The ratio between the bevel wheel 44 formed in the whirl and its driving wheel 45 is the same as the ratio 75 between the power-operated bevel wheel 49 at the bottom of the horn and its driven bevel wheel 48 and thus it will be understood that when the power-operated bevel wheel is rotated the whirl will be rotated at 80 the same speed and in the same direction but that a movement of the horn about its pivot will not turn the whirl with relation to the needle.

The needle thread comes from the thread 85 lock in the base of the machine and enters the horn through the hollow vertical shaft 50 about which the horn turns, it also passes up within the horn through a guide or guides and then through the thread eye 41 90 in the whirl to the work. If as is shown in the drawings the thread-receiving orifice of the thread eye in the whirl is eccentric to the axis about which the whirl and the horn turn a turning movement of the horn or 95 of the whirl will vary the length of thread passing between the whirl and the usual thread lock located in the base of the machine. This has been found to lead to uncertainty in the formation of the lock 100 stitch and, in the construction herein described, in order to obviate this a thread roller 51 is mounted within the base of the horn so as to deflect the thread to the opposite side of the axis about which the horn 105 turns to that on which the passage in the whirl lies. The thread roller is secured upon the upper end of the hollow shaft 50 which carries the bevel gear wheel for rotating the whirl, and is thus rotated with the whirl 110 so that it and the thread passage through the whirl always maintain a fixed relation with regard to one another. The distance of the thread roller from the axis of rotation 115 of the horn is such that as the horn turns, the amount of thread given up by the whirl is taken up by the thread roller or vice versa. Accordingly, rotation of the horn or of the whirl will not cause any appreciable tightening or slackening of the thread. 120

It will be understood that although the whirl above described embodies the present invention in its preferred form a whirl which differs only from prior constructions in that the thread-receiving orifice of its thread passage is located in or substantially in the axis of rotation of the whirl, comes within the scope of the present invention.

While it is preferred to employ the specific construction and arrangement of parts 130

shown and described, it will be understood that this construction and arrangement is not essential except so far as specified in the claims, and may be changed or modified 5 without departing from the broader features of the invention.

The invention having been described, what is claimed is:

1. A lock stitch sole sewing machine, having in combination, a straight barbed needle, a shoe supporting horn, a looper located in the horn, a discoidal shuttle rotating in a plane inclined to the path of the needle, means for imparting a plurality of revolutions to the shuttle for each reciprocation of the needle, and means for reciprocating the shuttle bodily in a substantial axial direction toward and from the path of the needle.

2. A lock stitch sole sewing machine, having in combination, a straight barbed needle, a shoe supporting horn, a looper located in the horn, a discoidal shuttle rotating in a plane inclined to the path of the needle, a casing in which the shuttle is mounted, a shuttle driver also mounted in the casing, means for imparting a plurality of revolutions to the shuttle driver for each reciprocation of the needle, and means for reciprocating the casing to move the shuttle in a substantially axial direction toward and from the path of the needle.

3. A lock stitch sole sewing machine, having in combination, a straight barbed needle, a shoe supporting horn, a looper located in the horn, a discoidal shuttle, a casing in which the shuttle is mounted, a shuttle driver also mounted in the casing, co-axial telescoping shafts for imparting to the shuttle driver a plurality of revolutions for each reciprocation of the needle, and means for reciprocating the casing to move the shuttle in a substantially axial direction toward and from the path of the needle.

4. A lock stitch sole sewing machine, having in combination, a straight barbed needle, a shoe supporting horn, a looper located in the horn, a discoidal shuttle, a casing in which the shuttle is mounted, a shuttle driver also mounted in the casing, co-axial telescoping shafts for imparting to the shuttle driver a plurality of revolutions for each reciprocation of the needle, an eccentric, and a link connecting the eccentric and casing for reciprocating the casing to move the shuttle in a substantially axial direction toward and from the path of the needle.

5. A lock stitch sole sewing machine, having in combination, a straight barbed needle, a shoe supporting horn, a looper located in the horn, a discoidal shuttle having a beak adapted to engage the loop of thread drawn by the needle, and a positioning device arranged to move into engagement with both sides of the loop of needle thread between

the work and the point at which the beak of the shuttle engages the loop and aline said loop with the beak of the shuttle.

6. A lock stitch sole sewing machine, having in combination, a straight barbed needle, a shoe supporting horn, a looper located in the horn, a discoidal shuttle having a beak adapted to engage the loop of thread drawn by the needle, a loop positioning device on the opposite side of the needle to 70 that on which the shuttle is located, and means for actuating said device to engage the loop of needle thread between the work and the point at which the beak of the shuttle engages the loop and aline said loop with 80 the beak of the shuttle.

7. A lock stitch sole sewing machine, having in combination, a straight barbed needle, a shoe supporting horn, a looper located in the horn, a discoidal shuttle having 85 a beak adapted to engage the loop of thread drawn by the needle, and a loop positioning device actuated by the needle actuating mechanism to engage the loop of needle thread between the work and the point at 90 which the beak of the shuttle engages the loop and aline said loop with the beak of the shuttle.

8. A lock stitch sole sewing machine, having in combination, a straight barbed needle, a shoe supporting horn, a looper located in the horn, a discoidal shuttle having a beak adapted to engage the loop of thread drawn by the needle, a loop positioning device comprising a lever having one end 100 arranged to engage both sides of the loop of needle thread between the work and the point at which the beak of the shuttle engages the loop and aline said loop with the beak of the shuttle and an actuating cam engaging the other end of the lever.

9. A lock stitch sole sewing machine, having in combination, a straight barbed needle, a needle bar, a shoe supporting horn, a looper located in the horn, a discoidal shuttle having a beak adapted to engage the loop of thread drawn by the needle, a loop positioning device comprising a lever having one end arranged to engage the loop of needle thread and aline said loop with the 110 beak of the shuttle, and an actuating cam on the needle bar arranged to engage the other end of the lever.

10. A sole sewing machine having in combination, a straight barbed needle, a shoe supporting horn, a looper located in the horn, a thread supply point at the base of the horn, and means intermediate the thread delivery orifice of the looper and said supply point for counteracting the tendency of a 120 rotation of the horn to tighten or slacken the thread.

11. A sewing machine, having in combination, a straight barbed needle, a shoe supporting horn, a whirl located in the tip 130

of the horn, a thread supply point at the base of the horn, and a thread guide having a movement with relation to the horn during the turning movement of the horn, and acting as the horn is rotated to maintain substantially constant the length of thread between the whirl and the thread supply point.

12. A sole sewing machine, having in combination, a shoe supporting horn, a whirl located in the tip of the horn, a thread supply point at the base of the horn, a thread

guide located with relation to the thread eye of the whirl upon the opposite side of the axis about which the horn rotates, and arranged to maintain constant its position with relation to the thread eye of the whirl during the rotating movement of the horn. 15
